J. W. DUNHAM

PROTRACTOR ATTACHMENT FOR SQUARES

Filed April 29, 1925

FIG. 1.

FIG. 2.

FIG. 3.

Inventor

James Wesley Dunham.

By Adam C. Fisher.

Attorney

UNITED STATES PATENT OFFICE.

JAMES WESLEY DUNHAM, OF BURNABY, BRITISH COLUMBIA, CANADA.

PROTRACTOR ATTACHMENT FOR SQUARES.

Application filed April 29, 1925. Serial No. 26,780.

To all whom it may concern:

Be it known that JAMES WESLEY DUNHAM, a subject of the King of Great Britain, residing at Burnaby, British Columbia, Dominion of Canada, has invented certain new and useful Improvements in Protractor Attachments for Squares, of which the following is a specification.

This invention is an attachment for mechanic's squares, such as try-squares, and the object is to provide a simple, practical and efficient attachment which may be easily mounted upon a try-square, and which will afford a ready means for laying down angles upon the work.

In the drawing—

Figure 1 is a top plan view showing the attachment as mounted upon a try-square, and with the protractor attachment set as 20 for an angle of 45 degrees;

Figure 2 is a bottom plan view;

Figure 3 is a detail of the protractor attachment blank.

The invention consists of a rectangular sheet metal body portion or plate 1 having a flange 2 turned perpendicularly along one edge, the said flange being medially slotted as shown at 3 in a longitudinal direction. The element so formed is now adapted to set 25 upon the stock 4 of the try-square 5, with the slot 3 engaging the blade 6 of the try-square, and the flange 2 engaging the inner edge 11 of the stock 4, that is to say, the edge of the stock from which the blade 6 extends. A relatively short, arcuate slot 7 is cut adjacent the inner corner 8 of the portion 1, that is to say, adjacent the outer end of the slot 3 and concentrically with 30 that corner 8, and a set screw 9 is passed down through the slot 7 and seated in the stock 4. The body portion 1 is thus pivotally secured to the stock 4 in such manner that the slotted end 10 of the flange 2 bears upon the said inner edge 11 of the stock 4 35 and serves as a pivotal bearing upon which the body portion 1 may be swung away from or towards the stock 4, in the laying out of angles on the work, while the slot 7 moves over the set screw 9. An integral, 40 curved finger 12 extends from the body portion 1 at the point relatively nearer to the

opposite end of the body portion, and reaches outwardly and backwardly in a curve that is concentric with the slot 7 and the corner 8.

A relatively long slot 13 is cut in this finger 12 concentrically with the slot 7; and a threaded stem 14 is set through this slot 13 and is anchored in the outer end of the stock 4. A thumb nut 15 is mounted on the 55 extended end of the stem 14. By this means, the body portion 1 may be locked rigidly at any desired angle relative to the stock 4. A calibrated angle scale 16 is cut along one edge of the slot 13. This attachment may 60 be readily mounted upon any try-square and affords a handy means for laying out angles upon any work.

While I have herein described a certain specific manner and method of constructing 70 and assembling the elements of my invention, it is understood that I may vary from the same in minor details, not departing from the spirit of my invention, so as best to construct a practical device for the purpose intended, as defined in the appended 75 claim.

I claim:

In combination with a try square, a protractor attachment therefor, comprising a 80 rectangular plate having a flange turned perpendicularly along one edge, the said flange being longitudinally slotted at one end for engaging the blade of the square, while the flange itself is adapted to engage that 85 edge of the stock of the square from which the blade of the square extends; the said plate having a relatively short, arcuate slot cut in the said plate adjacent the slotted end of the said flange and concentric therewith; the said plate having an outwardly and 90 backwardly directed arcuate finger pierced with a relatively long arcuate slot formed concentrically with the said short arcuate slot, and having a calibrated scale 95 cut along one edge thereof; a set screw passed through the short slot and anchored in the stock of the square; and a thumb screw locking element passed through the long slot and anchored in the said stock. 100

In testimony whereof I affix my signature.

JAMES WESLEY DUNHAM.
